UNITED STATES PATENT OFFICE.

AARON R. MANLEY, OF SAN JOSÉ, CALIFORNIA.

ROOF-SCAFFOLDING.

SPECIFICATION forming part of Letters Patent No. 283,908, dated August 28, 1883.

Application filed May 26, 1883. (No model.)

To all whom it may concern.

Be it known that I, AARON R. MANLEY, of San José, Santa Clara county, State of California, have invented an Improvement in 5 Roof-Scaffoldings; and I do hereby declare the following to be a full, clear, and exact description thereof.

My invention relates to a device which I call a "roof-scaffolding;" and it consists of 10 plates to which boards for a scaffolding may be fixed, and to one end of which is hinged an adjustable brace, while to the other end is hinged a bar or plate, which lies along the inclined roof, and has a gage-bar fixed to it, 15 this inclined bar and the brace serving to level the one which supports the staging, and adjust it to a roof of any pitch, as will be more fully explained by reference to the accompanying drawings, in which—

20 Figure 1 is a view of my device. Fig. 2 is a perspective view.

In laying shingles, building chimneys, and doing other similar work upon roofs, it is necessary to have horizontal stagings to work 25 from, and those are usually constructed by nailing temporary wooden supports to the roof and then laying boards or planks upon them. This is inconvenient, as it takes time to change them from place to place, and causes 30 some damage to the roof.

In my invention, A is a bar or plate, having screw-holes by which a plank or board may be permanently attached to it. At one end of this bar is a hinge-joint, by which a 35 slotted bar, B, is connected with it, and a second bar, C, is attached to the bar B by a screw and thumb-nut, D, so that it can be adjusted by means of the slot and made to overlap upon the bar B more or less. The second bar, C, is also slotted, to allow the lower 40 end of a brace, E, to pass through it. This brace is made extensible, and is hinged to the opposite end of the bar A from the bar C. In the present case I have shown the extensions as effected by forming a screw-thread upon the part E', which is hinged to the end 45 of A. The part E is hollow and threaded internally, so that the part E' screws into it, and the brace may thus be lengthened or shortened at will.

The operation will thus be as follows: There

are as many of these supporting hinged brackets secured to the staging board or plank as may be necessary, and the bars B C lie upon the roof in a line from the ridge to the eaves, 55 or in the plane of the incline. Sharp teeth or points *a a* project from the lower face of the bar B, so as to enter the roof and prevent it from sliding downward. The brace E passes through the slot *b* in the bar C, having a neck 60 which will slide along the slot at will, while the lower end, below the bar C, is made broad enough not to draw through the slot unless turned edgewise, and is sharpened, so that it will enter the roof, and thus hold itself at any 65 desired point. This extension-bar E E' is lengthened or shortened to suit the angle of the roof, and is moved along the slot *b* to such a point as will level the staging when it is set firmly into the roof, and the staging is ready 70 for work.

When the roof is to be shingled, the length of overlap of the shingles is usually marked by means of a chalk-line before laying each course. In my invention the bar C, which 75 overlaps the bar B, or rather extends up beneath it, is of sufficient thickness so that its upper end forms a shoulder, which will serve as a gage for each course when the staging is set. The amount of overlap being deter- 80 mined, the bar C is adjusted upon the bar B by its thumb-screw, and the shoulder will then always give the same distance.

This staging can be easily placed or moved from point to point with but little delay or 85 loss of time, and no damage to the roof. It is firm and secure when in place.

Having thus described my invention, what I claim as new, and desire to secure by Letters Patent, is—

1. A roof staging or scaffolding consisting of plank-supporting bars A, having hinged to one end spiked or toothed bars B C, which lie upon the inclined surface, and to the opposite end extensible adjustable braces E E', by 95 which they are supported and leveled, substantially as herein described.

2. In a roof staging or scaffolding, the horizontal plank-supporting bars, having extensible braces hinged to their outer ends, and 100 passing through guiding-slots *b* in the inclined extensible bars, which are hinged to the op-

posite end and lie upon the roof-surface, substantially as herein described.

3. In a roof staging or scaffolding, the horizontal plank-supporting bars, having extension-braces hinged to their outer ends, and the inclined toothed bars B, hinged to their inner ends, so as to lie upon the roof-surface, in combination with the adjustable extension and gage bar C, substantially as herein described.

In witness whereof I have hereunto set my hand.

AARON R. MANLEY.
